UNITED STATES PATENT OFFICE.

PAUL CRICCHIO, OF NEW YORK, N. Y., ASSIGNOR TO MAJESTIC LAMP WORKS, OF NEW YORK, N. Y., A PARTNERSHIP CONSISTING OF PHILIP SILBERHARTZ, JACOB SILBERHARTZ, AND HARRY SCHEINER.

DESIGN FOR A TABLE LAMP OR ARTICLE OF ANALOGOUS NATURE.

Application filed September 5, 1928. Serial No. 28,050. Term of patent 7 years.

To all whom it may concern:

Be it known that I, PAUL CRICCHIO, a citizen of the United States, and a resident of New York, county of Bronx, and State of New York, have invented a new, original, and ornamental Design for a Table Lamp or Article of Analogous Nature, of which the following is a specification, reference being had to the drawings, forming a part thereof.

In the drawings:

including a trunk-like base surmounted by shrubbery, and

Figure 2 is a perspective view of the base portion taken from a different angle than Figure 1.

I claim:

The ornamental design for a table lamp or article of analogous nature substantially as shown and described.

PAUL CRICCHIO.
